SQUARE

Ignatius B. Bialkowski, Buffalo, N. Y.

Application April 8, 1940, Serial No. 328,420

7 Claims. (Cl. 33—114)

This invention relates to a square for general use by mechanics and the like.

Various forms of squares and combination rules have heretofore been proposed wherein provision has been made for adjusting or separating the various elements of the devices. The present invention proposes a try-square construction wherein a head portion and an angularly related blade portion may be readily assembled and disassembled. An important consideration affecting proposed designs of this nature is that of insuring absolute accuracy of the assembled relation of the parts of the device at all times and without the necessity for checking or inspecting the accuracy of such assembled relation. This is particularly true in the case of tool makers, die makers, and other artisans and mechanics whose work requires extreme accuracy.

An important advantage of the construction herein proposed resides in the fact that if, by reason of wear or otherwise, the proper angular relationship of the head and blade of the tool is disturbed, or if the absolute straightness of either element is impaired by reason of becoming nicked, warped, or otherwise mutilated, the elements may be separated, reground, and reassembled without change or adjustment in the attaching and assembling elements of the tool and without the necessity for any special rechecking of their final assembled accuracy. Further, the novel tool of my invention may, by disassembly, be reduced to small compass for packing or transportation.

An exemplary specific embodiment of a try-square embodying the principles of my invention is set forth in detail in the following description and is illustrated in the accompanying drawing, wherein:

Fig. 1 is an elevational view of the assembled try-square with a portion of the head thereof broken away for clearness and with a preferred form of assembling and disassembling wrench in operating position with respect to the try-square;

Fig. 2 is a cross sectional view through the head portion of the try-square taken on the line 2—2 of Fig. 1; and,

Fig. 3 is a perspective view of the locking rod and securing nut of the form of invention illustrated in the preceding figures.

In the drawing, like characters of reference denote like parts throughout the several figures, and the numeral 10 designates a head or stock element for the try-square, such element being preferably substantially rectangular in cross section. A slot is formed in one end of the head

element 10 to receive a relatively flat blade element 11 which, in the illustrated instance, is arranged to extend at right angles to the head element.

In the preferred form the upper and lower edges of the blade element 11 are formed to precise parallelism and the bottom of the slot in the head element 10 is formed in exact angular relation with respect to the right-hand or inner working edge of the head element 10, that angle 10 in the present instance being 90°. It will be seen from the foregoing that assurance of intimate and secure contact of the lower edge of the blade element 11 with the bottom of the slot in the head element 10 absolutely insures correct 15 angular relationship of the working edges of the blade element 11 with respect to the working edge of the head element 10.

In practice, the width of the slot in the head element 10 is made just sufficiently large to conveniently accommodate the thickness of the blade element 11, but it will be seen hereafter that the arrangement of the head and blade element securing parts and their cooperation is such that substantial clearance between the thickness of 25 the blade and the width of the slot will not affect rigidity and accuracy of the assembled tool.

One of the flat surfaces of the blade element 11 is provided, adjacent its point of insertion in the slot in the head element 10, with a surface recess 30 12 which is of inverted L-shape and thereby provides a locking portion 13, for receiving a locking rod and a reduced entrance portion 14.

The head element 10 is provided with an elongate opening which extends from its lower end, as 35 seen in Figs. 1 and 2, nearly up to its upper end, but stopping short thereof to make for greater neatness and simplicity of appearance of the tool. This opening communicates with the slot in the upper end of the head element 10 at one side, for 40 which reason it is axially off-set with respect to the slot. The axis of the elongate opening is disposed at a slight angle with respect to the direction of extent of the head element 10 and this angularity is such that the opening, in its downward course, slants in a direction toward the vertical plane of the slot in the upper end of the element 10. A locking rod or pin 15 is disposed in the elongate opening of the head element 10 when the parts are in their assembled 45 position. The lower end of the locking pin 15 is preferably threaded as at 16 and the lower end of the elongate opening in the head element 10 is enlarged to receive a circular nut 17, such enlargement providing a ledge 18 against which 50

the nut 17 is adapted to seat. The upper portion of the nut 17 as viewed in the drawing is internally threaded and the lower portion thereof is provided with a noncircular opening which may 5 be hexagonal, as in the illustrated instance, for receiving the end of a manipulating wrench. One form of such wrench is shown in dot-and-dash lines at 19 in operating position in the opening in the nut 17 in Fig. 1.

10 Adjacent its upper end the locking rod 15 is notched to provide an overhanging ledge 20 which, in assembled position, seats upon the lower edge of the portion 13 of the recess 12 in the face of the blade element 11. Above the overhanging ledge 20 the locking pin 15 is flattened as at 21 to accommodate the body portion of the blade element 11 and give broader bearing contact of the under surface of the ledge 20 on the lower side wall of the recess portion 13 than 15 would otherwise be the case. The notch which forms the overhanging ledge 20 is undercut a degree sufficient to compensate for the angularity of disposition of the locking pin 15 with respect to the plane of the blade element 11 so that the 20 overhanging ledge 20 may have flat and continuous contact with the upper surface of the lower edge of the portion 13 of the recess 12.

The head element 10, the blade element 11, and the locking pin 15 are shown in Fig. 2 in their 30 respective assembled positions. It will be seen, however, that if, through the medium of the wrench 19 or the like, the nut 17 be further rotated to engage a greater length of the threads 16 at the lower end of the locking pin 15, the engagement of the upper end of the nut 17 against the ledge 18 will result in a tendency of the locking pin to be forced downwardly in the direction of its prearranged angular disposition. Such movement will not only result in a greater downward force of the overhanging ledge 20 against the bottom surface of the recess portion 13, but, 40 by virtue of the angular disposition of the locking pin 15, will have a definite horizontal force component (to the left as viewed in Fig. 2) which urges the blade element 11 intimately into engagement with the left-hand wall of the slot in the upper end of the head element 10, as viewed in Fig. 2. Stated another way, there is in effect, in the locking operation, a wedging of the upper 45 end of the pin 15 between the blade 11 and the opposite wall of the pin receiving opening. See Fig. 2.

It is for this reason that formation of the slot 55 in the head element 10 and the thickness of the blade element 11 to precisely the same dimension is not critical in constructing a tool according to the principles of my invention, and in fact, even though for general reasons it is desirable to so construct the parts initially, the blade element 60 11 may subsequently have its surface reground within reasonable limits without impairing the accuracy and continued utility of the tool upon subsequent reassembly.

65 While the tool so far illustrated and described is in the form of a try-square with the head and blade portions at an angle of 90° with respect to each other, it will be apparent that other angular relationships are within the purview of my invention, and in fact, a number of different 70 ly related angular blades may comprise a set of blades for use with a single head element. Similarly, a number of blades varying in length may be provided for use with a given head element and blades projecting in opposite directions from the slotted head element may be employed to

form T-squares. In the case of blades extending at angles other than 90°, each blade will have a portion of its lower edge so arranged as to be seated against the lower edge of the slot in the head element 10 at right angles to the working edge of the latter, and another angularly related portion arranged to extend at the desired angle with respect to the working edge of the head element 10.

When it is desired to disassemble the head and blade elements 10 and 11, respectively, it is merely necessary to loosen the nut 17 by use of the wrench 19. A very small degree of such loosening permits the blade element 11 to be moved to the right, as viewed in Fig. 1, until the entrance portion 14 of the recess 12 in the blade element is in alignment with the overhanging ledge 20 of the locking pin 15, whereupon the blade element may be removed by upward movement as viewed in Fig. 1. Subsequent reassembly is effected by a reversal of this process.

It is to be noted that the recess portion 13 extends substantially above and to the right of the upper end of the locking pin 15 as viewed in Fig. 1. For this reason both the side and end edges of the blade element 11 may be reground without interfering with later reassembly of the device. If the left-hand end of the blade 11 as viewed in Fig. 1 be ground, the locking pin 15 will merely be disposed farther to the right in the recess portion 13 when the parts are reassembled. To insure alignment of the left side of the head element 10 and the left end of the blade 11, also as in Fig. 1, the tool may be placed with such side and end surfaces on a surface plate or the like while the locking pin is being tightened.

As is customary in tools of this class, the working surface of the head element 10 is relieved as at 24 to avoid any interference with the full availability of the angularly arranged working edges of the head element 10 and the blade element 11.

It will be apparent to those skilled in the art that certain changes may be made in the details of construction of the form of invention 45 herein illustrated without departing from the spirit or scope of my invention as defined in the appended claims.

I claim:

1. In a square, a head portion having a slotted end, and a blade adapted to be rigidly disposed in said slotted end, a locking rod disposed in an opening in said head portion and extending therethrough obliquely, means at one end of said locking rod for engaging said blade and means 55 at the other end of said locking rod for cooperation with the adjacent end of said head portion to urge said locking rod outwardly of said opening whereby to exert an oblique force against said blade to urge it simultaneously against the bottom and one side wall of said slot.

2. In a square, a head portion having a slotted end, and a blade adapted to be rigidly disposed in said slotted end, said blade having a recess 65 in a face thereof adjacent said head portion, said recess comprising a portion extending lengthwise of said blade and spaced from a longitudinal edge thereof and a recess portion extending transversely from said edge to said first recess portion, a locking rod disposed in an opening in said head portion and having a projection at one end for engagement with said recess and means at its opposite end accessible from the opposite end of said head portion for moving said rod lengthwise to dispose said pro- 70

jection against a wall of the lengthwise portion of said recess and secure the blade against movement with respect to said head portion.

3. In a square, a head portion having a slotted end, and a blade adapted to be rigidly disposed in said slotted end, said blade having a recess in a face thereof adjacent said head portion, said recess comprising a portion extending lengthwise of said blade and spaced from an edge thereof and a recess portion extending from said edge to said first recess portion to provide an entrance to said lengthwise recess portion, a locking rod disposed in an opening in said head portion and extending therethrough obliquely, a projection at one end of said locking rod for engagement in said recess and means at the other end of said locking rod for cooperation with the adjacent end of said head portion to urge said locking rod outwardly of said opening whereby to exert an oblique force against said blade, said oblique force having a component downwardly into said slot and a component against the recess-bearing face of said blade to urge the latter firmly against a side wall of 25 said slot.

4. In a square, a head portion having a slotted end, and a blade adapted to be rigidly disposed in said slotted end, a locking rod disposed in an opening in said head portion and extending therethrough, means at one end of said locking rod for engaging said blade and means at the other end of said locking rod for urging said locking rod outwardly of said opening whereby to urge said blade securely into said slotted end, said means comprising a nut disposed in an enlargement of said opening, said enlargement providing a ledge against which the end of said nut bears, said nut having an axial opening therethrough, the inner end of said opening being threaded to engage threads formed on the end of said locking rod and the outer end of said opening being noncircular to receive wrench means.

5. In a square, a head portion and a blade adapted to be rigidly disposed at an angle with respect thereto, a slot in an end of said head to receive said blade, said head having an opening extending from the end opposite said slot to a point of communication with said slot, said blade having a recess portion in one face thereof so disposed as to be concealed by the slotted end of said head portion when the parts are assembled and a transverse entry recess portion

extending from the inner longitudinal edge of said blade to said first recess portion, a locking member disposed in said opening and having means adjacent said opposite end of the head for moving said member in a direction outwardly of said opposite end and for locking said member in such outwardly moved position, said locking member having a projection at its inner end for engagement in the recess in said blade to engage said blade and hold it forcibly in the bottom of 10 said slot by moving said member outwardly to locking position.

6. In a square, a head portion having a slotted end, a blade adapted to be rigidly disposed in said slotted end, said blade having a recess in 15 a face thereof adjacent said head portion, said recess comprising an oblong portion extending lengthwise of said blade and spaced from its longitudinal edges, and a recess portion extending transversely from one longitudinal edge of said 20 blade to one end of said oblong recess portion to provide an entrance to the oblong recess portion, a locking rod disposed in an opening extending lengthwise of said head portion, a projection at one end of said locking rod for engagement in said oblong recess portion, and means at the other end of said locking rod for cooperation with the adjacent end of said head portion to urge said locking rod outwardly of said opening to urge said projection forcibly against the 30 longitudinal wall of said oblong recess portion which is adjacent the transverse entrance recess portion and thereby secure said blade in said slotted end.

7. In a square, a head portion having a slotted 35 end, and a blade adapted to be rigidly disposed in said slotted end, said blade having an L-shaped recess in a face thereof adjacent said head portion, said L-shaped recess comprising a leg extending lengthwise of said blade intermediate of 40 the side edges thereof and a second leg extending transversely from a side edge of said blade to said first mentioned leg, a locking rod disposed in an opening extending lengthwise in said head portion and having a projection at one end 45 for engagement in said recess and means at its opposite end accessible from the opposite end of said head portion for moving said projection against a lateral wall of the first mentioned leg of said recess, the second mentioned leg of 50 said recess comprising an entrance portion for assembling said projection in said recess.

IGNATIUS B. BIALKOWSKI.
